UNITED STATES PATENT OFFICE.

FRED A. RICHARDS, FREDERIC C. BOCHATEY, AND JOHN T. JONES, OF GOLDEN, COLORADO; SAID JONES ASSIGNOR TO SAID RICHARDS AND SAID BOCHATEY.

HOSE CLAMP.

Application filed November 2, 1922. Serial No. 598,644.

To all whom it may concern:

Be it known that we, FRED A. RICHARDS, FREDERIC C. BOCHATEY, and JOHN T. JONES, citizens of the United States, residing at Golden, in the county of Jefferson and State of Colorado, have invented certain new and useful Improvements in Hose Clamps; and we do declare the following to be a full, clear, and exact description of the invention, such as will enable others skilled in the art to which it appertains to make and use the same.

Our invention aims to provide a simply constructed and inexpensive clamp whereby a hose, such as a fire hose, may be compressed or flattened to cut off the flow of water.

In carrying out the above end, we provide a base, a hose clamping lever fulcrumed on said base, and a hand lever engaged with said hose clamping lever for operating the same, a further aim being to provide an eye at the upper side of the base with which a claw-like end of the hand lever is engaged for operating the other lever, after which said hand lever may be partly inserted through said eye to hold the two levers in operative position.

A still further object is to provide an anti-friction roller and unique mounting means therefor, facilitating insertion of the hand lever into and withdrawal of said lever from the eye.

With the foregoing in view, the invention resides in the novel subject matter herein-after described and claimed, the description being supplemented by the accompanying drawing.

Figure 1 is a side elevation.

Figure 2 is a top plan view.

Figure 3 is a view similar to Fig. 1 showing a different position of parts.

Figure 4 is a detail section on line 4—4 of Fig. 2.

In the drawings above briefly described, the numeral 1 designates a suitable base which may well be formed of wood provided with a metal cover 2 suitably secured thereto by rivets or the like 3. In the present showing, one end of the base 1 is reinforced by upper and lower transverse bars 4 and 5 which are riveted or otherwise secured thereto, the ends of the bar 5 being by preference bent downwardly and suitably shaped

55 to form prongs 6 which prevent slippage

of the base upon the pavement or any other surface which may support it.

Suitably secured to and rising from the bar 4 are a pair of bearing lugs 7 to which one end of a hose clamping lever 8 is fulcrumed, as indicated at 9. The other end of lever 8 is preferably offset as seen at 10, is bent laterally as indicated at 11 to form a shoulder for engagement with a hand lever 12, and is finally bent again to provide a finger 13 which is spaced from and parallel to the body portion of the lever 8.

The hand lever 12 engages the bent portion 11 of the lever 8 between the body of this lever and the finger 13 and is provided with a claw-like end 14 which is engageable with an eye 15 at the upper side of the base 1, whereby swinging of said hand lever 12 toward the base will flatten the hose H placed upon said base between the lugs 11 and the eye 15, as shown fully in Fig. 3. Then, by inserting the lever 12 partly through the eye 15, said lever will engage the base and eye in a binding manner, thereby holding the clamping lever 8 in operative position. If desired, we may provide a pin 16 for passage through an opening 17 in the hand lever 12 to prevent it from being accidentally withdrawn from the eye 15. This pin may well be connected with the base by a suitable chain or the like 18.

The eye 15 is preferably formed by a U-bolt whose arms 19 are reduced and pass through the base 1 and its metal cover 2. These arms also extend through outwardly extending ears 20 on a pair of upright bearing lugs 21 which are located at opposed sides of an opening 22 formed in the base and cover plate. A roller 23 is mounted between these bearings on a suitable pin 95 or the like 24. This construction facilitates insertion of the lever 12 into the eye 15 and withdrawal of said lever, as will be readily understood.

It will be seen that the device may readily be carried wherever its use is necessary and may be quickly and easily applied to a hose and operated for cutting off the flow of water. As excellent results may be obtained from the details disclosed, they are preferably followed, but within the scope of the invention as claimed, numerous minor changes may be made.

We claim:

1. A hose clamp comprising a base; a

110

lever fulcrumed on said base for clamping a hose against the same, an eye on the upper side of said base beyond which said lever swings to clamping position, and a hand lever having a claw-like end engageable with said eye, said hand lever having an operating connection with the first mentioned lever, whereby swinging of said hand lever toward said base will move said first named lever to hose clamping position, said hand lever being then insertible partly through said eye to hold the first named lever in operative position.

2. A hose clamp comprising a base, a hose clamping lever fulcrumed on said base for clamping a hose against the same, the free end of said lever being bent laterally and then further bent into parallel relation with the body of said lever, an eye on the base beyond which said bent lever end swings when moved downwardly, and a hand lever having a claw-like end received in said eye, said hand lever engaging said bent end of said hose clamping lever to establish an operating connection between said levers, said hand lever being partly insertible through said eye to retain the two levers in operative position.

3. A hose clamp comprising a base and a hose clamping lever fulcrumed on said base, said base having an opening beyond which said lever swings when lowered, a pair of bearings at opposed sides of said opening

having horizontal ears contacting with the base, a U-bolt having its ends passed downwardly through said base and said ears and securing them together, a roller in said opening mounted between said bearings, and a hand lever engaged with said clamping lever and having a claw-like end received in said U-bolt, said hand lever being insertible partly through said U-bolt for binding engagement with said bolt and roller to retain the two levers in operative position.

4. A hose clamp comprising a base, a hose-engaging lever pivoted at one end on said base, the opposite free end of said lever being bent upon itself to provide a substantially U-shaped portion, the bight portion of which constitutes a shoulder and the extremity of which is disposed in spaced parallelism to the body portion of the lever and forms a confining finger, an operating lever for said first named lever, a portion of said operating lever being disposed between said finger and said body portion and bearing on said shoulder, and means for pivotally connecting the lower end of said operating lever to said base.

In testimony whereof we have hereunto affixed our signatures.

FRED A. RICHARDS.
FREDERIC C. BOCHATEY.
JOHN T. JONES.
